UNITED STATES PATENT OFFICE.

JOSEPH E. PERRAULT, OF WATERTOWN, MASSACHUSETTS, ASSIGNOR TO HOOD RUBBER COMPANY, OF WATERTOWN, MASSACHUSETTS, A CORPORATION OF MASSACHUSETTS.

BINDING-ROLLER MACHINE.

Application filed September 15, 1921. Serial No. 500,846.

To all whom it may concern:

Be it known that I, JOSEPH E. PERRAULT, a citizen of the United States, and a resident of Watertown, in the county of Middlesex and State of Massachusetts, have invented certain new and useful Improvements in Binding-Roller Machines, of which the following is a specification.

My invention relates to a machine or apparatus designed to roll down and press into firm and smooth adherence the binding strips or foxing commonly applied at or to the edges of the soles of rubber footwear.

The present invention aims to provide a simple, durable and efficient machine by which such action may be much more expeditiously performed with a resulting increased uniformity in product and with a material saving in labor costs.

20 The invention includes the novel features of construction and arrangement and combination of parts hereinafter described and particularly defined by the appended claims.

An embodiment of my invention is illustrated in the accompanying drawings, in which—

Figure 1 is a side elevation.

Fig. 2 is an end view.

Fig. 3 is a section on line 3—3 of Fig. 1.

30 Figs. 4 and 5 are detail views of the last support adjusting means.

Figs. 6 and 7 are detail views of the inclined arm controlling connections.

The machine is shown in the drawings as 35 preferably arranged in duplex form so as to be capable of operating upon two shoes, the elements being so arranged and timed that the shoes or other articles of footwear may be removed and replaced alternately.

40 Referring by reference characters to this drawing, 1 and 1^a designate lasts upon which the footwear is to be supported during the rolling operation, and as the supporting and cooperating mechanism for both 45 are the same, a description in the singular will suffice. Each last is mounted on or carried by a support 2 through the intermediary of a heel support 3 and a toe support 4, the heel support having a projection 3^a 50 designed to engage a recess in the last.

The heel support 3 is slidably carried by a vertically adjustable member 5 which has a guideway therein by which the member 3 is guided in its reciprocating movement and 55 the member or support 3 is adapted to be

moved towards and from the toe support by suitable means such as a screw-threaded rod 6 engaging a threaded opening through the support 3, the screw being journaled in suitable bearings provided on the member 5 60 and having a non-circular head 6^a by which it may be turned. In a similar manner the toe support 4 is slidably carried by the support 2 through the provision of a suitable guideway and an operating screw 7, having 65 a gear connection 7^a with screw 6, these adjustments being designed to accommodate varying sizes of lasts. The last supporting member 5 is vertically adjustable to provide for variations in the heights of lasts, such 70 vertical adjustment being conveniently secured by providing the member 5 with a depending bar or rod 5^a which is provided with a rack *a* meshing with a gear carried by the shaft of a suitable operating wheel 8. Associated with the last is presser means preferably in the form of a pair of presser rollers 9 and 10 which are designed to press upon and roll down the binding strip or foxing in the manner hereinafter described, the 80 roller 9 when in engagement with the foxing lying in a substantially vertical position or perpendicular to the sole of the last and the roller 10 in an inclined position (preferably at an angle of approximately 45°). 85 While the presser rollers are thus held in contact with the foxing, relative movement of the roller-carrying means and the last-support is effected whereby the rollers 9 and 10 are caused to roll completely around 90 the edge of the sole preferably first in one direction and then in another so as to apply the foxing firmly and smoothly to the shoe edge. In my preferred embodiment of the invention, this movement is accomplished 95 by mounting the support 2 upon a vertical shaft 11 journaled in the base frame 12, upon which shaft are provided upper and lower beveled gears 13 and 14 which are loose on the shaft and which mesh with a 100 beveled gear 15 carried by a driving shaft 16 which may be driven in any suitable manner from any desired source of power, as for instance by a sprocket chain (not shown) passing around the sprocket wheel 17. The 105 gears 13 and 14 have reversely placed clutch faces or members 13^a and 14^a which are designed to be alternately engaged by coacting clutch faces 18^a and 18^b. These clutch faces 18^a and 18^b are carried by a sleeve 18 110

2
splined on the shaft, which sleeve is encircled by a collar member 19 within which collar the sleeve is rotatably mounted but with which it has suitable annular flange engagement so that endwise movement of the collar will produce corresponding movement of the sleeve and clutch faces.

The collar is provided with a cross head 19^a which is connected by springs 20 with the base frame, which springs supplement the action of gravity and tend to hold the parts in such position as to clutch the lower gear 14 to the shaft 11. Shaft 16 carries a cam 21 which is designed to coact with a suitable contact portion carried by the collar, the cam having such a contour that during a certain portion of its movement it will raise the collar and sleeve to unclutch the gear 14 from the shaft and clutch the gear 13, whereby the shaft 11 will be rotated in one direction while during the remaining portion of the cam the parts will be lowered to unclutch the gear 13 and clutch the gear 14 to effect a reverse rotation of the shaft.

25 The collar is held against rotary movement by forks or lugs 19^c engaging a stationary guide rod or bar 22 carried by the main frame. The roller 9 is carried by a vertical shaft 9^a articulated on the base frame at 9^b, the roller being journaled on the frame in any suitable manner as shown. Roller 10 is journaled on an arm 10^a and is preferably in the shape of a floating roller being capable of longitudinal movement 30 along the shaft against the pressure of the centralizing springs 23 and 24. Shaft or arm 10^a is articulated at 10^b to a support 25 and has fast thereon a plate or bracket member 10^c provided with an arcuate slot c' 35 which is engaged by a transverse pin 26^a carried by a pull rod 26, the pin and slot constituting a lost motion connection. Pull rod 40 is connected at 26^b to the one arm of a bell crank lever 27 fulcrumed on the base frame and having its other arm provided with a roller 27^a designed to coact with a cam 28 fast on shaft 16. The roller carrying arm of bell crank lever 27 is connected by a link 29 and pin and slot or lost motion 45 connection c² with an arm 9^c of the shaft 9^b on which lever 9^a pivots so that when bell crank lever 27 is rocked by the high part of cam 28, lever 9^a will be swung on its pivot to remove the roll 9 from the shoe at the same time that the pull rod 26 is actuated to 50 remove the roll 10 from the shoe, such removed positions being shown on the right of Fig. 1. A spring 30 connected to arm 9^a tends to rock the arm 9^a so as to bring the roll 9 into contact with the shoe and a spring 31 through flexible band 31^a passing over guide roller 31^b tends to rock the arm 10^a on its pivot 10^b to bring the roll 10 into contact with the shoe, such contacting position 55 being shown at the left of Fig. 1, at which

time the roller 27^a coincides with the low part of the cam 28.

Each sprocket or driving member 17 is preferably arranged to be controlled by a machine stop mechanism of any approved type, indicated conventionally at 32 and controlled by foot lever 33 and so arranged that by pressing upon the lever 32 the corresponding roller mechanism will operate through a complete cycle and be automatically stopped at the completion, such stop being so timed that the high part of the cam 28 will be in contact with roller 27^a and the parts shown in the position shown in Fig. 1, allowing removal of the last carrying the finished shoe and its replacement by a fresh last.

During this time the companion parts will be in operation as indicated on the left in Fig. 1.

As such machine stop mechanisms are well known and form per se no part of the present invention, conventional illustration thereof is deemed sufficient.

What I claim is:

1. In apparatus of the class described a last support, means for rotating the same on an axis substantially perpendicular to the sole, and opposed cylindrical rollers located on opposite sides of the sole, one of said rollers being journaled on an axis substantially parallel with the axis of the last and the other roller being journaled on an axis inclined to the axis of the last, and means for pressing the rollers towards each other.

2. In apparatus of the class described, a last support, means for rotating the same alternately in opposite directions, and rolling presser means journaled on a relatively stationary axis for coacting with the article carried by the last.

3. In apparatus of the class described, a last support, means for rotating the same about a fixed axis, a roller having means for yieldingly pressing it into contact with the sole edge portion of the last, and means for positively moving said roller away from the last.

4. In apparatus of the class described, a last support, means for rotating the same about a fixed axis, a plurality of rollers positioned to coact with the edge portions of the last and having their axes relatively inclined, and means for moving said rollers towards and from the last.

5. In apparatus of the class described, a last support, means for rotating the same about a fixed axis, a plurality of rollers positioned to coact with the edge portions of the last and having their axes relatively inclined, spring means for pressing said rollers towards the last, and means for positively moving said rollers away from the last.

6. In apparatus of the class described, a last support, means for rotating the same on an axis substantially perpendicular to the plane of the face of the last sole, and an associated pivoted arm carrying a floating presser roller and yielding means for centralizing said roller.
7. In apparatus of the class described, last supporting means, presser roller supporting means, one of said means being revolvable relative to the other on an axis substantially perpendicular to the plane of the sole of the last, said presser roller supporting means including a pivoted arm, and a floating presser roller carried by said arm.
8. In apparatus of the class described, a last support, means for rotating the same on an axis substantially perpendicular to the plane of the sole of the last, and an associated pivoted arm, a roller journaled on said arm to have endwise movement thereon, and centering springs acting against opposite ends of said roller.
9. In combination a last support carrying a last, a swinging arm carrying a roller positioned to act on the edge of the sole portion of the last, yielding means tending to press said arm towards the last, and cam controlled means for swinging said arm away from the last, said cam controlled means embodying a lost motion connection.
10. In combination a last support, a last carried thereby, a swinging arm carrying a roller positioned to act on the edge of the sole portion of the last, means for alternately rotating said last support in opposite directions, yielding means tending to press said arm towards the last, and cam controlled means for swinging said arm away from the last, said cam controlled means embodying a lost motion connection.
11. In combination, a vertically adjustable last support, a last carried thereby, roller supporting means carrying a roller positioned adjacent the sole of the last, one of said parts being revoluble to cause the rollers to travel around the edge of the sole, and means for yieldingly pressing the roller towards the last and withdrawing it therefrom.

In testimony whereof, I affix my signature.

JOSEPH E. PERRAULT.
